BOTTLE CAP

Leonard Abbotts, Bridgeport, Conn., assignor to
The Bridgeport Metal Goods Manufacturing
Company, Bridgeport, Conn., a corporation of
Connecticut

Application November 18, 1937, Serial No. 175,215

8 Claims. (Cl. 215—43)

This invention relates to new and useful improvements in bottle caps, and has particular relation to ornamental caps for bottles such as perfume bottles, lotion bottles, etc.

5 An object of the invention is to provide a cap of the kind indicated and including an inner or bottle closure shell and an outer ornamental shell securely and yet inexpensively assembled and held in the finished product by an improved 10 mechanical construction which does not require soldering or welding operations.

Another object is to provide an improved method of assembling caps of the character described.

15 Other objects and advantages will become apparent from a consideration of the following detailed description taken in connection with the accompanying drawing wherein a satisfactory embodiment of the invention is shown. However, 20 it is to be understood that the invention is not limited to the details disclosed but includes all such variations and modifications as fall within the spirit of the invention and the scope of the appended claims.

In the drawing:

25 Fig. 1 is a vertical central sectional view showing the first step in the assembling of the present cap;

Fig. 2 is a detail sectional view through a portion of a completed cap;

30 Fig. 3 is a bottom plan view of the outer shell employed;

Fig. 4 is a top plan view of the inner shell of the cap;

35 Fig. 5 is a transverse section substantially on line 5—5 of Fig. 1;

Figs. 6 and 7 are detail sections substantially on lines 6—6 and 7—7 respectively of Fig. 5;

40 Fig. 8 is a vertical sectional view through a somewhat different cap but made in accordance with the invention; and

Fig. 9 is a horizontal sectional view taken as 45 along the line 9—9 of Fig. 8.

Referring in detail to the drawing and at first particularly to Figs. 1 through 7 the improved cap includes an inner shell 10 comprising a top 11 and a screw threaded skirt or side wall 12. About its open end shell 10 is provided with an outwardly directed annular flange 13 and inwardly of such flange but below or outwardly of the threads the skirt is provided with an annular bead 14. The upper or inner wall 15 of the bead is at a gradual slope or incline while its lower or forward wall 16 is at a steep or sharp incline.

50 An outer shell 17 receives the inner or bottle neck closing shell 10 and is here shown as substantially in the form of a ball. It may, however, be of other shapes as desired. This shell 17 is provided with an opening 18 of a diameter

to receive the skirt portion of the shell 10 but of less diameter than the bead 14.

At spaced points notches 19 are provided in the edge portion of the opening 18 and at correspondingly spaced points in its sides the inner 5 shell is provided with short ribs 20. In assembling the cap the outer shell 17 is placed or telescoped over the closed end of the shell 18 as in the dotted line position of Fig. 1. Then the edges of the opening 18 being on the rear or gradually inclined wall 15 of bead 14, the partial assembly is placed in a press and the edge of the opening 18 snapped over the bead 14 moving shell 17 from the dotted to the full line position of Fig. 1. The metal of the shell is 15 sufficiently resilient to permit the edges of the opening to pass over bead 14 and then spring or snap in under this bead as shown. Although the edge of the opening passes over the upper 20 more gradually inclined wall 15 of the bead under pressure, due to the steeper lower wall 16 on the bead it will require a much greater force to pass it back over the bead to separate the cap and shell and they are therefore effectively held against separation in use.

25 Next the flange 13 is rolled over onto the edge portion of the outer shell about the opening 18 so as to clamp such edge portion against the sharp or steep face 16 of the bead 14. In this way the two shells are securely attached to one 30 another against separation. When placing the shells one over the other care should be taken to have the notches 19 of shell 17 register with the ribs 20 of shell 10. Then when the shells are pressed together the interlocking ribs and 35 notches prevent any relative turning of the shells.

It will be evident that the amount the metal of the shell 17 can yield to pass over the bead 14 and then snap under this bead to give a tight connection is limited. Therefore where a particularly strong and rigid connection is desired between the outer shell 17 and inner shell 10 to 40 overcome unusual strains additional securing means may be provided. Thus after these shells 45 are forced together portions of the bead 14 may be forced outwardly to form a further grip between the two shells. Thus by means of a suitable tool, such as a punch, acting against the inner wall of bead 14 lugs 23 may be forced outwardly against the inner wall of shell 17 and as 50 these lugs extend outwardly further than the bead 14, they overlap the shell 17 to a greater extent and thus provide a firmer and stronger grip 55 between the two shells and one which is much harder to break or loosen than that of the bead 14 alone. Any suitable number of these lugs 23 may be provided as desired, but for the usual tops three as shown are found to be sufficient. It is of 60

course to be understood these additional lugs 23 may or may not be used as is found desirable.

It is not necessary that the outer shell 17 be a ball or round. It need only be of a shape such 5 that the lower portion 17a is turned in sufficiently so that it can spring over the bead 14 as described.

The bottle cap shown in Figs. 8 and 9 includes the outer shell 17 secured to an inner shell 21 in the manner and by the method described when 10 considering Figs. 1 through 7. The cap of Figs. 8 and 9 differs from the cap of the first described figures only in that shell 21 does not have its skirt portion screw threaded, but in lieu of screw threads is provided with a pair of spring fingers 15 22 lanced and pressed from opposite sides thereof to frictionally engage the neck of any bottle to which the cap may be applied. This automatically adjusts itself to variations in the diameter of the bottle neck. The outer shell 17 and inner 20 shell 21 are secured together in the same manner and by the same construction as are shells 10 and 17 of Figs. 1 to 7.

From the above description it will be clear that the inner and outer shells of the improved cap are 25 secured together without the use of solder or welding. The shells are mechanically connected in such manner that one may not pull out of or off the other and there can be no turning of the shells relatively. A neat and secure connection is 30 provided, and since the edges of the shells have a complete annular clamping relation there can be no bending sideways of one shell relative to the other. In short the inner shell or cap will not turn in the outer shell or ball, it cannot be pushed 35 in or pulled out and cannot be bent sideways, and still it is held in mechanically and is not soldered or welded. As above suggested the outer shell may be of the desired shape, the invention not being limited to the use of a ball shaped shell, and 40 it is also mentioned that the outer shell may be colored or otherwise ornamented as desired.

Having thus set forth the nature of my invention, what I claim is:

1. In a bottle cap, an inner shell to receive and 45 close the neck of a bottle, said shell having an annular shoulder on its outer wall inwardly of its open end, an outer shell having an opening receiving said inner shell and having its portion about said opening turned inwardly and engaging the forward face of said shoulder, and said inner shell having its edge portion turned over onto the edge portion of the outer shell to retain it against said 50 forward face of said shoulder.

2. In a bottle cap, an inner shell open at one 55 end to receive the neck of a bottle, an outwardly directed flange at the open end of said shell, an outwardly directed bead on said shell inwardly of said flange, an outer shell having an opening therein and having its edge portions about such 60 opening located between said flange and bead, and said flange clamping such edge portions against such bead whereby the shells are secured together.

3. In a bottle cap, an inner shell open at one 65 end to receive the neck of a bottle, an outwardly directed flange at the open end of said shell, an outwardly directed bead on said shell inwardly of said flange, an outer shell having an opening therein and having its edge portions about such 70 opening located between said flange and bead, said flange clamping such edge portions against such bead to secure the shells together, and interlocking means on the inner and outer shells whereby relative turning of the shells is prevented.

4. In a bottle cap, an inner shell open at one end to receive the neck of a bottle, an annular outwardly directed flange about the open end of said shell, an annular outwardly directed bead on said shell inwardly of said flange, an outer shell having an opening therein and having an 5 annular edge portion about said opening located between said flange and bead, and said flange clamping said annular edge portion against said bead whereby the shells are secured together. 10

5. In a bottle cap, an inner shell open at one end to receive the neck of a bottle, an outwardly directed flange at the open end of said shell, an outwardly directed bead on said shell inwardly of said flange, an outer shell having an opening 15 therein and having its edge portions about such opening located between said flange and bead to secure the shells together, and lugs pressed outwardly from the bead against the inner wall of the outer shell and extending beyond the bead 20 to provide an additional securing means between the shells.

6. In a bottle cap, an inner shell open at one end to receive the neck of a bottle, an outwardly directed bead on said shell adjacent said open 25 end, said bead having a gradually inclined inner face facing away from the open end of the shell and a more sharply inclined forward face facing toward the open end of the shell, and an outer shell having an opening therein of a smaller 30 diameter than said bead and enclosing the inner shell with the edges of the opening engaging the more steeply inclined forward face of the bead to prevent longitudinal separation of the shells whereby the outer shell may be secured to the 35 inner shell by forcing it over the bead from the inner face thereof.

7. In a bottle cap, an inner shell open at one end to receive the neck of a bottle, an outwardly directed bead on said shell adjacent said open 40 end and having a sharply inclined forward face facing toward the open end of the shell and a less sharply inclined face facing away from the open end of the shell, and an outer shell of larger 45 diameter than the inner shell having an inwardly inclined end portion provided with an opening of less diameter than the outer diameter of the bead, adapted to be forced over the bead from its less sharply inclined face whereby said inner shell may be located within said opening with the 50 edges of the opening engaging said forward face of the bead to hold the shells against longitudinal separation.

8. In a bottle cap, an inner shell open at one end to receive the neck of a bottle, an outwardly 55 directed bead on said shell adjacent said open end and having a sharply inclined forward face facing toward the open end of the shell and a less sharply inclined face facing away from the open end of the shell, an outer shell of larger 60 diameter than the inner shell and having an inwardly inclined end portion provided with an opening of less diameter than the outer diameter of the bead adapted to be forced over the bead from its less sharply inclined face whereby said 65 inner shell may be located in said opening with the edges of the opening engaging the forward face of the bead to prevent withdrawal of the inner shell from the opening, and lugs pressed outwardly from the bead against the inner wall 70 of the outer shell and extending beyond the bead to provide an additional securing means between the shells.

LEONARD ABBOTTS.
